UNITED STATES PATENT OFFICE.

POTVENT INGE CREWS, OF MERIDIAN, MISSISSIPPI.

BALING-PRESS.

SPECIFICATION forming part of Letters Patent No. 392,785, dated November 13, 1888.

Application filed April 4, 1888. Serial No. 269,562. (No model.)

To all whom it may concern:

Be it known that I, POTVENT INGE CREWS, of Meridian, in the county of Lauderdale and State of Mississippi, have invented a new and 5 Improved Baling-Press, of which the following is a full, clear, and exact description.

My invention relates to presses for baling cotton, hay, straw, or other material, and has for its object to provide a simple, inexpensive, 10 easy-working, and substantial press of this character, which may be operated to form good bales with economy of time and labor.

The invention consists in certain novel features of construction and combinations of parts 15 of the baling-press, all as hereinafter described and claimed.

Reference is to be had to the accompanying drawings, forming a part of this specification, in which similar letters of reference indicate 20 corresponding parts in all the figures.

Figure 1 is a sectional side elevation of my improved baling-press with the follower down. Fig. 2 is a plan view thereof with parts in horizontal section on the line $\alpha\alpha$ in Fig. 1. 25 Fig. 3 is a sectional side elevation of the press with the follower raised. Fig. 4 is an end view of the press, taken at right angles to Fig. 3; and Fig. 5 is a transverse vertical section taken on the line yy in Fig. 1.

30 This press is designed more particularly for pressing cotton as it comes from the gin; but it is applicable for use in baling hay, straw, or other material.

The main frame A of the press consists of 35 suitably framed and bolted timbers having a sill or base, a , on which the follower B is supported when down by shoulders b' on its four upright legs, b , which next the shoulders b' are provided with sharpened lower ends, b^2 , which 40 enter holes a' in the sill, as shown in Fig. 1 of the drawings. These legs b also form long guides to the movement of the follower up into the baling-box C, which consists of upright planks held to the main frame A, and opening 45 at the top to the bale-chamber D, which comprises a suitable top platen, E, and four vertical walls fitted to the frame to receive the bale and made adjustable in any approved way to allow removal of the bale after it is 50 tied in the chamber. The side walls and a part of the frame or backing thereof are indicated

by dotted lines in Figs. 1, 3, and 4 of the drawings. The follower and platen are provided with the usual transverse slots for admitting the ties while tying out the bales.

55

The lower parts of the two end walls of the baling-box C are formed as doors F F, each of which is made with two upright side pieces, f , connected to upper and lower cross-pieces, $f' f^2$, and hung by a bar and staples, G, or other suitable hinge, to the main frame A, so as to open upward. Between the parts $f f$ of each door is fitted a vertically-movable bar or plate, h , to which is fixed a transverse latch-bar, H, which, as the door closes downward, 60 is adapted to engage and lock behind beveled and notched catches I, fixed to the frame A, or to the adjacent fixed portions of the baling-box walls. The latch-bar H normally rests by its gravity upon the lower cross-piece, f^2 , of 65 the door F, and the bar or plate h of the latch extends below the door, so as to be raised to 70 lift the latch from the catches by one of the toggle-levers which operates the follower, as presently explained.

75

The follower is operated by a system of compound toggle-levers consisting of two long levers, J J, which are pivoted at their inner upper ends by pins or shafts j to the under side of the follower, and two opposite pairs of 80 shorter levers, K K, each pair of which is pivoted by a pin, k , to the sill a of the main frame, and the outer ends of each pair of levers K K are pivoted by a pin or shaft, k' , to one of the longer levers J at some little distance from the outer ends of these levers, which are preferably forked and are provided with a shaft on which is journaled a series of pulleys or sheaves, L—three, four, or more—in the end of each lever J, three being shown in the 85 drawings. The ends of the levers J K are preferably fitted into rounded sockets or recesses M in the follower and sill, and the levers J J and K K K K are so pivoted that their rounded ends bear on each other while 90 they rest in the sockets M, and whereby the strain on their pivot pins or shafts is reduced to a minimum. Metal wear and anti-friction plates may be fitted at the joints between the levers and their sockets M to insure continued 95 ease and smoothness of working and durability of the entire system of toggle-levers, which 100

are operated by a wire rope and drum, forming a powerful windlass, and as next described.

The windlass-rope N, which is preferably made of wire, is fastened at *h* at one end to one of the long toggle-levers J, and thence the rope is passed across to the other lever and around one of its pulleys or sheaves L, and thence back and around one of the pulleys L of the first-named toggle-lever, and thence backward and forward to and around successive pulleys L for the entire series of pulleys in both the levers J J, and from the last pulley of the series the rope is passed to the windlass drum O, which is journaled in substantial timbers P P, held to the press-frame A. The shaft of the drum is formed or provided with cranks R, by which to turn the windlass by hand, and the drum may have additional radial bars, *o*, forming hand-levers to assist in turning the windlass, and if it is desired to operate the press by other than hand-power a pulley, S, may be fixed to the drum-shaft to receive a belt from any convenient motor.

The operation of the baling-press is very simple and effective and as follows: When the follower B is down, as shown in Fig. 1 of the drawings, its legs *b* rest on the frame-sill *a* to relieve the toggle-levers of the weight of the cotton or other material thrown into the baling-box C to be pressed, and the doors F of the box will be closed and held shut by the latches H engaging the catches I. When sufficient material for a bale has been put into the baling-box, the windlass-drum O will be turned to wind the rope N on it, and this will raise the toggle-levers to lift the follower, somewhat quickly at first, but with a gradually-decreasing speed of travel as the pressing of the bale between the follower and platen progresses, thus applying the increasing power of the compound levers to meet the increasing resistance to compression of the cotton or other material. As the levers J rise toward the latch-bars *h*, and just after the platen has moved above the end doors F, the latches H will be lifted from the catches I by the contact of the levers J with the latch-bars, which releases the doors F and allows the levers J to swing the doors

open upward on their hinges to give room for these levers to enter the baling-box to carry the plunger upward to the extreme of its effective stroke to complete the pressing of the bale, which will then be tied and discharged, and the windlass-rope N will then be slackened off to allow the follower B to fall by its gravity, and as the follower-levers J pass below the doors F or their latch-bars *h* these doors close and are again latched at H I about as the follower comes to a rest by its legs *b* on the frame-sill *a*, and all is now ready for refilling the baling-box and turning the windlass drum for pressing the next bale in a manner above described.

The upper platen, E, is preferably made removable to allow the baling-box to be filled with material to be pressed from the top of the bale-chamber; but said platen may be fixed to the press-frame, if desired, and the material to be baled will then be fed into the baling-box below the platen, as will readily be understood.

Having thus described my invention, what I claim as new, and desire to secure by Letters Patent, is—

1. The combination, in a baling-press, of a frame, a baling-box and chamber provided with a follower, toggle-levers pivoted to the follower and the press-frame, said baling-chamber formed at one end with hinged doors, latches on the doors, and catches on the frame adapted to hold said doors closed and to be tripped by the toggle-levers to allow the doors to open to admit the levers into the baling-chamber during the effective stroke of the follower, substantially as herein set forth.

2. The combination, in a baling-press, of a baling-box, a follower therein, toggle-levers, and connected mechanism for operating the follower, said baling-box provided with hinged doors F and sliding latches *h* thereon, and catches I on the press-frame, substantially as herein set forth.

POTIVIENT INGE CREWS.
